UNITED STATES PATENT OFFICE.

CHARLES M. DRINKWATER, OF KOKOMO, INDIANA.

ASH-SIFTING APPARATUS.

1,290,725.

Specification of Letters Patent.

Patented Jan. 7, 1919.

Original application filed December 20, 1917, Serial No. 208,047. Divided and this application filed April 29, 1918. Serial No. 231,477.

To all whom it may concern:

Be it known that I, CHARLES M. DRINKWATER, a citizen of the United States, residing at Kokomo, in the county of Howard and 5 State of Indiana, have invented certain new and useful Improvements in Ash-Sifting Apparatus, of which the following is a specification.

My present invention pertains to ash sifting and analogous apparatus, and is designed more particularly, though not necessarily, for embodiment in the apparatus constituting the subject of my contemporary application filed December 20, 1917, Serial Number 15 208,047 of which this application is a division.

One of the objects of the present invention is the provision of an ash-sifting or analogous apparatus in which the throat usually employed to support a dust-confining valve is joined to the body on which it is mounted in such manner that the escape of dust between the two is absolutely precluded.

Another object of the invention is the provision of an ash-sifter body susceptible of being expeditiously and easily knocked down or taken apart so as to occupy but small compass in storage or shipment, and one adapted to be as readily set up with its parts joined 30 in such manner that it is ready for efficient use, and this without the employment of skilled labor.

Other objects and advantageous features of the present invention will be fully understood from the following description and claim when the same are read in connection with the drawings, accompanying and forming part of this specification, in which:

Figure 1 is a longitudinal vertical section 40 of so much of an ash-sifting apparatus as is necessary to illustrate the preferred application of my invention.

Fig. 2 is a vertical transverse section taken in the plane indicated by the line 2-2 of 45 Fig. 1.

Fig. 3 is a top plan view of a portion of the apparatus.

Similar numerals of reference designate 50 corresponding parts in all the views of the drawings.

My present invention is preferably, though not necessarily, embodied in an ash-sifting apparatus, and in addition to a throat 1 for supporting a flaring mouth 2 and a dust-confining valve 4 or the like, the apparatus com-

prises a body 12 on which the throat is superimposed. In the present and preferred embodiment of the invention there is an inclined sifting screen 13 in the body, a vertically-slidable door 14 disposed in guides at the forward end of the body for the convenient removal of cinders from the forward portion of the body bottom, a baffle plate 15 disposed at approximate right angles to the screen 13 and in spaced relation to the lower end thereof, a compartment 16 below the screen and isolated from a cinder compartment 17 by a transverse wall 18, and a drawer 19 designed to receive ashes and having handles 20 and 21 at its opposite ends; 70 said drawer being removable through an opening in the forward wall of body 12 and being flanged, as indicated by 22, to effectually close said opening when the drawer is in position to receive ashes.

The lower end of the throat 1 is provided with loop-flanges 23 that straddle the upstanding wall portions about the induction orifice of the body 12. Thus the throat is supported on the body in such manner that 75 the joint between the two is broken and the escape of dust precluded, and yet the throat may when necessity arises be readily lifted off the body and as readily replaced thereon.

The side walls 24 of the body 12 are provided on their upper edges with inwardly-directed flanges 25, Figs. 3 and 4, and the top wall 26 is interlocked with said flanges 25, as indicated by 27 to break joints between the parts, strongly connect the same, 90 and lend rigidity and strength to the body as a whole, as well as to permit of the wall 26 being drawn out of engagement with the walls 24 when it is desired to ship or store the body in a knock-down state. At its 95 lower end the wall 26 is interlocked with the upper end of the baffle plate 15, as indicated by 28, Fig. 1, and at its upper end said wall 26 is interlocked with an upstanding wall portion, as indicated by 29. Thus when it 100 is desired to remove the wall 26 from walls 24, it is simply necessary as a condition precedent to open the joints 28 and 29 whereupon the wall 26 may be withdrawn endwise from the position shown in Fig. 1. 105

The bottom wall 30 of the body 12 is connected by interlocked joints 31, Fig. 2, with the side walls 24, and hence said bottom wall is strongly connected to the side walls in a dust-proof broken joint manner, and yet 110

the bottom wall may be readily withdrawn from engagement with the side walls for knock-down purposes.

Fig. 3 brings out clearly the connection 5 of the front wall 32 of the body 12 to the side walls 24 thereof through the medium of interlocked joints 33 for dust-proof and strength-lending purposes as well as to permit of the front wall being readily drawn 10 out of engagement with the side walls for knock-down purposes, while the screen 13 is bolted to the side walls 24, as indicated by 15 34, the baffle plate 15 and wall 18 are also bolted to said side walls, as indicated by 20 35 and 36, respectively, the wall 18 is bolted to the screen 13, as indicated by 37, and the said screen is bolted to the front wall 32, as indicated by 38. Manifestly when the 25 said bolts are removed, the body walls may be disassembled in the manner before indicated for the purposes described, and when the said walls are relatively arranged and engaged in the setting up of the body and the bolts are placed and secured in position 30 a rigid and strong body will be produced.

When deemed expedient the screen 13 may be mounted in the body 12 so as to be slipped endwise into and out of working position, as when it is desired to use screens 35 having interstices of different sizes or to replace a worn-out screen with a new one. This, however, is not of the essence of my invention and I have therefore regarded it as unnecessary to illustrate same.

I have entered into a detailed description.

of the construction and relative arrangement of the parts embraced in the present and preferred embodiment of my invention in order to impart a full, clear and exact understanding of the said embodiment. It 40 is to be understood, however, that in the future practice of the invention such changes or modifications in the construction may be made as are fairly anticipated by and fall within the scope of my appended 45 claim.

Having described my invention, what I claim and desire to secure by Letters Patent, is:

A knock down receptacle for use as an 50 ash sifter, comprising sides having vertical rear edges and inclined forward edges, an inclined top having detachable slidable engagement with the inclined edges of the sides, an end having detachable slidable engagement with the vertical edges of the sides and spaced from the lower ends of said sides to provide a drawer opening, a bottom having detachable slidable engagement with the lower ends of said slides, and a throat 55 provided at its lower end with a surrounding socket to receive the upper ends of the sides, end and top.

In testimony whereof I affix my signature in presence of two witnesses.

CHARLES M. DRINKWATER.

Witnesses:

R. M. PARKER,
LUCY B. McCARTHY.
